Inventor
ANDREW E. GRISWOLD

Attorney
Richard J. Cook

UNITED STATES PATENT OFFICE.

ANDREW E. GRISWOLD, OF SEATTLE, WASHINGTON.

SWITCH.

Application filed April 20, 1921. Serial No. 462,818.

To all whom it may concern:

Be it known that I, ANDREW E. GRISWOLD, a citizen of the United States, and a resident of the city of Seattle, county of King, State of Washington, have invented certain new and useful Improvements in Switches, of which the following is a specification:

This invention relates to improvements in safety switches; and more particularly to switches of that character wherein the switch blades and jaws are contained within a box or housing, and a handle is provided for opening or closing the switch which is operable from outside of the housing.

The principal object of the present invention is to provide a safety switch of the above character, so constructed that the door of the switch housing, which is provided in order that access may be had to the switch mechanism, fuses, etc., can not be opened without first opening or causing the switch to be opened, nor can the switch be closed while said door is open.

Another object of the invention resides in the manner of mounting the switch operating handle which permits it to be dismounted and then moved within the switch box for shipping, or storage; thereby making possible closer and easier packing of such switches than is ordinarily possible.

Another object of the invention resides in the construction whereby the switch may, if desired, be locked in the "off" position to prevent its use by any unauthorized person.

A still further object resides in the provision of a hinge pin whereon the box door and the switch handle are pivotally mounted, which is constructed in such manner that, so long as the switch box door is closed and locked, the pin can not be removed and the door in this way removed and the switch tampered with.

In accomplishing these and other objects of the invention, I have provided the improved details of construction, the preferred forms of which are illustrated in the accompanying drawings, wherein—

Figure 1 is a front elevation of a safety switch embodying the present invention; the switch handle being shown in "off" position.

Figure 2 is a central vertical section of the same, with the switch shown closed in full lines and open in dotted lines.

Figure 3 is a front view of the switch when closed, with the upper portion of the

front wall of the box broken away to illustrate the interior parts of the switch.

Figure 4 is a horizontal section taken on the line 4—4 in Figure 2.

Referring more in detail to the several views of the drawings, wherein like reference numerals designate the same or like parts—

1 designates the switch box, or housing wherein the switch jaws and blades are contained. This box is preferably of rectangular form and is constructed of sheet metal, or other material and provided at the front with a door 2, which is adapted to close the lower half of the box, and which is hingedly mounted upon the lower horizontal edge of a plate 3 which is secured to and closes the upper portion of the front of the box; the door being mounted by means of two spaced apart hinges 4 and 5; the upper and lower sections of which are both joined by the same hinge pin 6.

At one end, the pin 6 has a laterally turned portion 7 which normally seats, when the door is closed, within cooperating notches or sockets 8—8' located respectively in the edge of the door adjacent the hinge and in the lower edge of the cover plate 3. This type of pin is used in order that, so long as the door is closed, the pin can not be removed to permit the door, or switch handle being tampered with by an unauthorized person, but which, upon opening the door, can be removed if it is desired to do so in order to remove the door or switch handle, as presently described.

Mounted pivotally upon the hinge pin 6 between the two hinges, and extending through suitable openings cut in the box cover plate 3 and door 2, is a switch handle 10. This, for a three pole switch as illustrated, comprises opposite side bars which are spread apart at their outer ends and have a gripping member 11 mounted therein, and which are drawn closely together at the mounting point through which the pin extends and have a plate 12 secured between them at this point which has a laterally extending ear or stop 14 on the under side thereof, Figure 2, which will engage the door 2 when the handle is moved downwardly, to limit its movement in this direction. Within the box, the side bars of the handle are bent laterally in opposite directions and then inwardly and at their inner

ends have the ends of toggle links 15 pivotally connected therewith which, in turn at their opposite ends connect with a bar 16 which is fixed, by means of plates 13 through 5 which it extends, to a series of switch blades 19 which are pivotally mounted at their lower ends between switch jaws 17 and, at their upper end, are adapted to be moved into and from switch jaws 18 by manipulation of the handle 10. The bar 16 is so mounted that the edges of the blades 19 are set within notches or grooves provided within it, so that it is prevented from slipping from place.

15 The switch jaws 17 and 18 are mounted upon an insulating block 20 that is fixed to the back wall and inside of the box, and circuit wires 21 and 22 are connected respectively with these jaws, as is best shown 20 in Figure 2; the wire 22 being connected through fuses 24, as is common practice.

To prevent unauthorized opening of the box, I provide the door 2 with a key controlled lock as is indicated at 25, or other suitable means such as would be provided to receive a pad lock.

At the upper edge of the plate 3 I have fixed a flange plate 25 which is adapted to extend beneath the horizontal flange 26 of the upper wall section of the box, so that this plate can not be removed while the door is locked even should the screws which hold it be removed.

35 For two and four pole switches, the construction of the handle would be slightly different from the one here shown, but would operate in the same manner and would not depart from the spirit of the invention.

Assuming that the switch box and mechanism are so constructed as described, and illustrated, it will be seen by reference to Figure 2 of the drawings, that by moving the outer end of the handle 10 downwardly, the inner end will move upwardly and, 45 through its connection by means of the links 15 with the switch blade actuating bar 16, will cause all of the switch blades to be moved into the jaws to close an electric circuit through the switch. It will also be noted that by moving the handle in the opposite direction the blades will be pulled outwardly and the switch opened.

It is apparent also that when the switch 55 is closed, the door can not be opened without causing the handle to be moved upwardly and the switch thereby opened; this being effected by engagement of the door as it is opened with the lateral extension 14 of the plate 12 that is secured between the handle forming members.

It is also noted that, should the switch be open and the door also open, the switch can not be closed so long as the door is open.

60 Normally when the switch is open, the parts assume the position in which they are

shown in dotted lines in Figure 2, but should it be desired to position them so that the switch can not be closed, the door is opened and the switch blades pulled farther downward so that the toggle links pass over the 70 dead center of the handle and the toggle extends on the opposite side of the handle, thus after locking the door, the switch can not be closed even by closing movement of the handle.

To facilitate the shipping, packing or storing of switch boxes of this character, I have provided that the handle be removed from the mounting pin and be moved into the box. This is effected without disconnecting 80 it from the switch, by first opening the door 2, which permits the end portion 7 of the pin to be unseated from the notches 8-8', and then removing the pin from the hinges so that the door and handle are released. 85 The handles may then be laid within the box and the door replaced and closed.

Having thus described my invention, what I claim as new therein and desire to secure by Letters-Patent, is:

90 1. A safety switch of the character described comprising a switch housing provided with an outwardly opening door, spaced apart hinges having the sections thereof fixed to the said housing and to the 95 door, a hinge pin extended through and pivotally connecting the sections of the hinges, a switch mechanism located within the housing, a switch handle pivotally mounted upon the hinge pin operatively connected at its 100 inner end with the switch mechanism and with an outer operating portion movable to open or close the switch while the housing door is closed, and adapted to be moved so as to open the switch by the opening movement of the housing door.

105 2. A safety switch of the character described comprising in combination, a switch housing provided at the front with an outwardly opening door, spaced apart hinges having the sections thereof fixed to said housing and to said door, a single hinge pin extended through and pivotally connecting the sections of both hinges, a switch mechanism within the housing and a handle operatively connected for operating the said switch mechanism, pivotally mounted on said hinge pin between the said hinges.

110 3. A safety switch of the character described comprising in combination, a switch housing provided at the front with an outwardly opening door, spaced apart hinges having the sections thereof fixed to said housing and to said door, a single hinge pin extended through and pivotally connecting the sections of both hinges, a switch mechanism within the housing and a handle operatively connected for operating the said switch mechanism, pivotally mounted on said hinge pin between the said hinges, a 115 120 125 130

plate fixed to said handle at the pivot point having an ear extending laterally therefrom outside of the housing for engaging the door to limit movement of the handle closing direction and which, if the switch is closed, will be engaged by the opening of the door to cause said switch handle to be moved to open position.

4. A safety switch of the class described comprising in combination, a switch housing closed at the front by a fixed wall and a door that is hingedly attached thereto, said wall and door having registering notches therein at the hinged edges, a pair of spaced apart hinges for mounting said door, the sections of which are fixed respectively to

said door and said fixed wall, a single hinge pin for both sets of hinge sections, having a laterally turned end portion adapted to extend through said notches to prevent removal of said pin when said door is closed, a switch mechanism within the housing, a handle operatively connected to operate the switch mechanism extending from the housing from between said hinges and pivotally mounted on the hinge pin, and a lock whereby the said door may be normally retained in closed position to prevent removal of the pin.

Signed at Seattle, Washington, this 14th day of April, 1921.

ANDREW E. GRISWOLD.
